ELOF H. MEDÉN, OF ELIZABETH, NEW JERSEY, ASSIGNOR, BY MESNE ASSIGNMENTS,
TO A. G. A. RAILWAY LIGHT & SIGNAL CO., INC., OF ELIZABETH, NEW JERSEY, A
CORPORATION OF NEW JERSEY.

RAILWAY SIGNALING DEVICE.

1,348,508.

Specification of Letters Patent. Patented Aug. 3, 1920.

Application filed February 15, 1918. Serial No. 217,299.

To all whom it may concern:

Be it known that I, ELOF H. MEDÉN, a subject of the King of Sweden, residing in the city of Elizabeth, county of Union, State of New Jersey, have invented certain new and useful Improvements in Railway Signaling Devices, of which the following is a specification.

My invention relates to railway signaling devices of a character in which different colored lights are provided for the purpose of indicating the condition of the track ahead, a red light constituting the danger signal, a yellow light the caution signal and a green light the clear signal.

The object of my invention broadly is to simplify the construction of such devices and at the same time render the same more positive and efficient in action.

A further object of my invention is to provide a signaling device for railways which may be operated economically as compared with similar devices as the same heretofore have been constructed and placed in operation.

A still further object of my invention is to provide a device in which normally the danger signal is displayed, but which upon the approach of a train, engine or the like will display a caution or clear signal, as the case may be.

Another object of my invention is to provide a signaling device which is well adapted for both daylight and night use.

Other objects and advantages of my invention will be referred to specifically in the detailed description thereof which follows or will be apparent from such description.

In the accompanying drawings forming a part of this specification I have illustrated certain forms of constructions showing certain embodiments of my invention, but it will be understood that the same is susceptible of embodiment in other forms of construction within the scope of the claims.

In the drawings:—

Figure 1 is a view showing, diagrammatically, a portion of railway track, track circuits, signal control circuits and signal devices operated thereby constructed in accordance with my invention;

Fig. 2 is a view partly in vertical sec-

tion and partly in side elevation of a signal light and the post supporting the same constructed and adapted to operate in accordance with my invention;

Fig. 3 is a view in elevation of the upper portion of the post and the signal, looking toward the left in Fig. 2;

Fig. 4 is a top plan view of the signal mechanism shown in Fig. 2, a portion of the casing surrounding the signal light being shown in horizontal section, but other portions of the apparatus shown in Fig. 2 being omitted;

Fig. 5 is a transverse sectional view taken on the line 5—5 of Fig. 2;

Fig. 6 is a view partly in central horizontal section and partly in top plan of the portion of the signal light mechanism shown in Fig. 4, the casing surrounding the signal light being omitted;

Fig. 7 is a vertical sectional view taken on the line 7—7 of Fig. 6;

Fig. 8 is a view partly in vertical section and partly in side elevation showing a modified construction of signal lighting apparatus embodying my invention;

Fig. 9 is a view similar to that shown in Fig. 8 showing still another modification of my invention;

Fig. 10 is a vertical sectional view of an electro-magnet and associated parts showing details of construction thereof.

In the drawings 1 designates a railway track over which pass railway trains, etc., indicated symbolically at 2, 2^a and 2^b. 3 designates the batteries of a track circuit including sections of the rails and the wires 4 and 5, each of the said circuits including electro-magnets 6. The sections of the rails referred to are included between the transverse heavy lines 7. These electro-magnets actuate and control armatures 10, 11 and 12, there being one set of armatures and one track circuit and electro-magnet for each section of railway track. These armatures 10, 11 and 12 constitute and form parts of the signal control circuits which extend through signal actuating or controlling electro-magnets 15 and 16, the energizing and deenergizing of which actuate and control the signal device or devices indicated diagrammatically or symbolically at 17, 17^a, 17^b, 17^c and 17^d in Fig. 1.

The signal 17 is shown in full lines in the caution position, while the signals 17^a, 17^c and 17^d are shown in the danger position. The signal 17^b is shown in the clear position.

5 20 designates batteries, there being shown one battery for each of the sections above referred to. These batteries furnish the current for the circuits including the electro-magnets 15 and 16 above referred to, 10 and it is the passage of current through these circuits that actuates or controls the signals 17, 17^a, 17^b, etc.

Tracing the current through the circuits controlling the signal 17^b, it will be found 15 to travel through the line 21, the armature 10, line 22, ground line 23, line 24, armature 11 (at the right hand side of Fig. 1) line 25, armature 12 (in the fourth group of armatures from the left in Fig. 1), line 26, 20 through the electro-magnet 16 and line 27 to battery 20.

It will also be noted that the circuit passes through the line 21, armature 10, line 22, ground line 23, line 28, armature 11 (in the 15 fourth group of armatures counting from the left in Fig. 1), line 29, electro-magnet 15 and line 27 to the battery 20.

It will thus be seen that when the signal is shown in clear position both of the electro- 30 magnets are energized. When in the caution position as shown at 17 in Fig. 1 only the electro-magnet 15 is energized. This may be seen or demonstrated by tracing the circuit from the battery 20 shown at the left 35 hand side of Fig. 1.

Normally and when the signal is in the danger position neither of the electro-magnets 15 or 16 is energized, so that the red light or danger signal is displayed. In 40 other words, normally the signal indicates danger, and it is only when a train, engine, etc., is approaching a signal and when the track ahead is clear that the signal device moves into the clear position indicating that 45 the train may proceed rapidly and without caution. In case, however, there are two trains in positions, such as the trains 2 and 2^a in Fig. 1, said trains being separated by an intervening section, such as is indicated between the lines 7—7 previously referred to, the signal 17 is caused to be moved into the caution position, as already stated. On the other hand should there be a train, such as 50 that indicated by the dotted lines at 31 in Fig. 1 in the section adjacent to that in which the train at 2 is located the signal 17 would remain in the danger position, that is, in a horizontal position as is the case with signal 17^a. This can be readily seen by 55 tracing the circuit from the battery 20 at the left hand side of Fig. 1 and assuming that a train is in a position indicated by dotted lines 31 in Fig. 1, in which case the track circuit will be short-circuited so that the 60 65 electro-magnet 6 would be deenergized, per-

mitting the armatures 10, 11 and 12 in the second group of armatures counting from the left of Fig. 1 to drop or fall so as to permit the armature 10 to fall against the contact 32, while at the same time permitting the armatures 11 and 12 to move away from the contacts 33 and 34.

The circuits and their general operation having been described, I shall now proceed with a description of the subsequent figures 75 in the drawings in which I have illustrated concrete embodiments of devices constructed in accordance with my invention.

Referring first to Figs. 2 to 7 inclusive, 80 40 designates a post or standard upon which the signaling apparatus for the respective sections of the system is supported. 41 designates a flasher device of any suitable known construction to which gas is supplied through a pipe 42 which should proceed 85 from a pressure regulator of any known construction. From the flasher the gas is conducted to a burner at 43. 44 designates a pipe for supplying gas for a pilot burner. Although I prefer to employ a flasher device 90 such as 41 because by its use a saving in gas can be effected, still it will be understood that the use of a flasher may be dispensed with in which case the burner 43 would remain at all times active.

95 The light from the burner 43 passes out through a condensing or other lens 50 which is supported in a frame 51 in a side of the casing 52 and at the center of a disk 53 supported upon said side of said casing.

100 The lens 50 is situated at the bottom of an open chamber 54, formed upon the disk 53, the said chamber being surrounded by a series of pockets or chambers 55 and the latter in turn being surrounded by a series 105 of pockets or chambers 56. These chambers or pockets are formed by laterally extending and projecting walls or flange like portions as is clearly shown in Figs. 2 and 3 of the drawings. The presence of these 110 walls shuts off the sunlight from the surface of the disk 53, that is, throws a shadow over the surface of said disk so that the light is rendered more plainly visible in the day time. By reason of thus producing a 115 shadow upon the surface of disk 53 the device is rendered more suitable for daylight work.

The color of the light rays which are transmitted through the lens 50 depends on 120 the position of the pivotally supported quadrant shaped member 58 having openings 59, 60 and 61 in which openings are situated glasses 59^a, 60^a and 61^a of different colors,—that in the opening 59 being red, that in 125 the opening 60 being yellow and that in the opening 61 being green, as illustrated in Fig. 7, the first indicating danger, the second caution and the third clear or no danger.

130 The quadrant shaped member 58 nor-

mally is in the position shown in the drawings with the light from the burner 43 showing through the red colored glass 59^a and the lens 50.

In order to counterbalance the weight of the portion of the member 58 containing the openings 59, 60 and 61, I have provided an extended portion 63 as clearly indicated in the drawings constituting a counterbalance weight. The quadrant shaped member 58 is rigidly and fixedly secured to a shaft 65 upon which is mounted an armature 66 between the poles 67 and 68 of an electro-magnet the coil of which is shown at 69 extending around the base 70 of said magnet, the said electro-magnet corresponding to the electro-magnet 16 shown in Fig. 1.

The shaft 65 is in alignment with a shaft 71, the said two shafts being connected so as to be relatively rotatable as will herein-after be described.

Shaft 71 is provided with an armature 72 which is situated between the poles of an electro-magnet, pole 74 only of which is shown in Fig. 6, the coil 75 of which is shown as being coiled around the base 76 of said magnet, the said electro-magnet corresponding to the electro-magnet 15 shown in Fig. 1. The shaft 65 is supported in bearings in the upper ends of posts 77, while the shaft 71 is supported in bearings in the upper ends of posts 78.

The shaft 71 is provided upon its inner end (which is in adjacent opposing relation to the inner end of shaft 65) with a sleeve 80, said sleeve being secured to the shaft 71 by means of a pin 81.

Sleeve 80 is provided with a projection 82 constituting a shoulder which engages a projecting end of a pin 84 which extends through the adjacent end of the shaft 65. Normally, that is, when the electro-magnets are deenergized or inactive the projecting portion of pin 84 is substantially in contact with the shoulder 82. When in such position the armature 72 is in the position shown in Fig. 7 of the drawings.

Both armatures 66 and 72 are of Z-shape. When in their normal, inactive positions as shown in Figs. 6 and 7, it will be noted that the armature 72 is in position with the projecting or Z-portions thereof overlapping to a considerable extent, as clearly shown in Fig. 7, portions of the pole members of the magnet with which it is associated, while the armature 66 is in what may be termed or described as substantially a neutral position with regard to the poles 67 and 68.

Assuming that the track is in condition with trains or engines 2 and 2^a in the positions shown in Fig. 1 of the drawings, it will be understood that the circuit through coil 75 of the magnet including the pole 74 would be completed and that a current would flow through the same thereby ener-

gizing the said magnet. The result of so energizing the same would be that the armature 72 would be caused to rotate a distance sufficient to move the opening 60 and glass 60^a into the position now occupied by the opening 59.

The glass 60^a in the said opening 60 being yellow would indicate caution to train 2. The movement of the armature 72 and the shaft 71 effects a corresponding movement 75 of the shaft 65 by reason of the engagement of the shoulder 82 upon shaft 71 with the projecting end of the pin 84 upon shaft 65.

The member 58 being secured to the shaft 65 moves with the latter. The extent of 80 the movement of the armature 72 and the shaft 71 is limited by contact of a projecting lug 85 upon the said armature with the end portion of the pole 73.

In case the track had been clear, that is 85 to say, in case the train or engine 2^a had not been present the condition of the signal controlling circuits would have been such, as has been shown already, that the second magnet comprising the coil 69 and poles 67 90 and 68 would have been energized, so as to cause a continuation of the movement of shaft 65 and the armature 66 secured to and carried thereby independently of shaft 71, so as to bring the opening 61 and glass 61^a 95 therein into the position now occupied by the opening 59 and glass 59^a situated therein.

It should be noted that the first or preliminary movement of shaft 65 effected by reason of contact of shoulder 82 with the 100 projecting end of pin 84 causes a movement of armature 66 into position to be fully acted upon by the lines of magnetic force between the poles 67 and 68 at the time of the cessation of the rotary movement of shaft 71. 105 The limit of the movement of the shaft 65 and armature 66 is controlled by the contact of the projection 90 with the end of the pole 67. Rotary movement of said shaft and armature in the opposite direction is 110 limited by contact of said projection 90 with the outer end of pole 68.

Immediately that the electro-magnets controlling the member 58 are deenergized the said member 58 returns by gravity into its 115 normal position as shown in the drawings in which the danger signal is displayed.

In the modified forms of construction shown in Figs. 8 and 9 of the drawings, I have omitted the pivoted oscillatory member 58 and instead thereof have provided a plurality of lights together with a plurality of stationary colored condensing lenses.

In these two forms of construction, I have 125 provided a device indicated as a whole by the reference numeral 91 for controlling and directing the flow of gas to whichever burner it may be necessary to light in order to display the signal required.

There are two of these devices provided for each signal lighting device. This is clearly shown in both of the Figs. 8 and 9.

The gas is admitted first to the lowermost 5 of the said devices through a pipe 92. The said pipe 92 communicates with a passage 93, formed in what may be termed or described as the base portion 94 of the said device 91. The passage 93 communicates 10 with passageways 95 and 96, the former leading to the second device 91 shown in both forms of construction.

The several devices 91 illustrated in Figs. 8 and 9 are identical in construction. The 15 base portion 94 of the said device 91 is provided with a depression 97 at its inner central portion in which is situated an electro-magnetically controlled valve 100 which operates to close either the passageway 95 or 20 the passageway 96 depending upon the condition of the electro-magnet 101 by means of which the said valve 100 is controlled. Normally the valve occupies a position to close the passageway 95. When in this 25 position the passageway 93 is in communication with the passageway 96 through the magnet core 103, the latter passageway being in communication with a pipe 104 through which gas is supplied to burner 30 105. Said burner is situated in rear of the red colored lens 106. In the construction shown in Fig. 8 of the drawings, the burner 105 is active at all times except when the magnet 101 is energized. However, it will 35 be understood that preferably a flasher device, such as is shown at 108 in Fig. 9 may be employed in order to render the operation of the device more economical. Further reference will be made to this flasher 40 device later on in this specification.

In case, however, the trains, engines, etc. should be in positions indicated by the reference numerals 2 and 2^a in Fig. 1 of the drawings the caution signal should be displayed. When in this position, and as has been previously described the electro-magnet 101 becomes energized with the result that the valve 100 is lifted from its seat so as to close the passageway 96 and simultaneously open the passageway 95 thus putting the passageway 93 into communication with the latter. The gas may pass, therefore, through the passageways 93 and 95 to the pipe 107 which is in communication 55 with the upper device 91, the construction of which is in all respects the same as is illustrated in Fig. 10 of the drawings so that the gas that passes from the pipe 107 into the said device is conducted through 60 passageways 93 and 96 to a pipe 110 leading to a burner 111 situated in rear of the yellow colored condensing lens 112. It will be seen that now the flame or light of burner 105 has been extinguished and the 65 burner 111 has been lighted.

Should it be that the track in front of the train indicated at 2 is clear the electro-magnet in each of the devices 91, shown in Figs 8 and 9 would be energized, as previously pointed out with the result that the 70 valve 100 in the uppermost of the devices 91, shown in each of the two figures, would be moved into position to close the passageway 96 and thus prevent the passage of gas into the pipe 110. Such movement, as 75 already described would put the passageway 93 into communication with passageway 95 so that the gas would pass through the upper device 91 into the pipe 115 leading to the uppermost burner 116 situated in rear 80 of the uppermost green colored condensing lens 117.

Constantly burning or lighted pilot burners 118 are provided for igniting the gas as it issues from the burners 105, 111, 116. 85 The pilot burners 118 are supplied with gas from a pipe 120 having connection in Fig. 8 at 121 with the lowermost device 91 in said figure. In Fig. 9 the pipe 120 instead of being connected with the lowermost device 91 is connected with a pressure regulator 125. Gas is supplied from any suitable source of supply through a pipe 126 to the said pressure regulator. The gas is led from the said pressure regulator 90 through a pipe 127 to the flasher 108. From the said flasher the gas is supplied at intervals through the pipe 92 (in Fig. 9) to the lowermost device 91. The flasher device 108 is not illustrated in further detail because 95 such devices are old and are at present in quite general commercial use.

In Fig. 8, as heretofore stated, the pipe 92 leads directly from the source of gas supply to the lowermost device 91. 105

In both forms of construction shown in Figs. 8 and 9 I have provided what may be described or defined as a hood 130 surrounding the lenses 106, 112 and 117, its purpose being to throw or cast a shadow over 110 the said lenses and the surfaces of the frames surrounding and supporting them in order to darken the same so that they may be more readily and clearly visible in the daylight. In the brighter portions of 115 the day, that is, the portions nearer noon time when the sun is nearer to or in a vertical position in the heavens the rays therefrom will strike the hood 130 and the latter will cast a shadow over the faces of the 120 lenses 106, 111, 117 and the frames surrounding the same, as stated above.

It is not so essential that a shadow be thrown over such lenses in the earlier or later portions of the daylight period when 125 the sunlight is not so bright.

In both forms of construction shown in Figs. 8 and 9 I have provided a casing 131 for inclosing the operative parts of the structure illustrated in said figures. The 130

lower portion of the casing in Fig. 9 is somewhat enlarged in order to enable it to receive and hold the flasher 108 in addition to the parts which are contained in the casing shown in Fig. 8.

In both forms of construction the lowermost devices 91 are supported upon the bottoms of the casings, while the uppermost of said devices are supported upon projecting flange-like portions 132 which extend inwardly from a side wall thereof, as is clearly shown.

I claim:—

1. In a railway signaling device, the combination of a track circuit, a signal controlling circuit controlled by said track circuit, a plurality of magnets adapted to be energized by said signal controlling circuit, said magnets being provided with rotatable armatures arranged in axial alinement, means having connection with said armatures and movable thereby for controlling the character of signal displayed by said signaling device, and means whereby during the operation of the said device the said armatures move during a certain period simultaneously and together, and during a further period relatively with respect to each other.
2. In a railway signaling device, the combination of a light, an arm situated in front of said light, said arm having different colored glasses situated at intervals therein which are adapted to be moved into position in front of said light, a track circuit, signal controlling circuits controlled by said track circuit, a plurality of magnets adapted to be energized by said signal controlling circuits, said magnets having rotatable armatures which are operatively connected together, and the said arm having connection with one of said armatures and being movable thereby.
3. In a railway signaling device, the combination of a light, an arm situated in front of said light and being provided with portions of transparent material of different colors situated at intervals therein, a track circuit, signal control circuits adapted to be controlled by the said track circuit and the latter adapted to be controlled by the train movements upon the track, a plurality of magnets, said magnets each having an armature, means for operatively connecting the said armatures, and the said arm having connection with one of said armatures and moving therewith.
4. In a railway signaling device, the combination of a light, an arm situated in front of said light, said arm being provided with a plurality of openings closed by transparent material of different colors which are adapted to be moved into position in front of said light, a track circuit, signal control circuits adapted to be controlled by said

track circuit, the latter adapted to be controlled by movements of trains upon the said track, a plurality of magnets controlled by said signal control circuits, said magnets each being provided with a rotatable armature, the axes of which are situated in alinement with each other, means for operatively connecting the said armatures to permit them to move in unison or relatively with respect to each other, and the said arm having connection with one of said armatures.

5. In a railway signaling device, the combination of a light, an arm situated in front of said light and having openings therein which are closed by transparent material of different colors, which openings are adapted to be brought into position in front of said light to control the character of signal displayed, the said signals indicating "danger," "caution" and "clear," and the said arm being normally in position with the "danger" signal displayed, a track circuit, two signal control circuits, an electro-magnet in each of said circuits, each magnet being provided with a rotatable armature, means for operatively connecting the said armatures so that they may rotate in unison, and also relatively to each other, the said arm having connection with one of said armatures and rotative movement of one of said armatures causing movement of said arm to the "caution" position, and the continued movement of the other armature causing movement of said arm to the "clear" position, the said arm having connection with the last mentioned armature.

6. In a railway signaling device, the combination of a light, an arm situated in front of said light, said arm having openings therethrough closed by transparent material of different colors whereby "danger," "caution" and "clear" signals may be displayed, a track circuit, signal control circuits controlled by said track circuit, electro-magnets situated in said signal control circuits, said magnets being independent of each other, and each being provided with a rotatable armature, said armatures being of Z-shape and one of said armatures overlapping the poles of the magnet with which it is associated while the other of said armatures is situated in a neutral position with respect to the poles of the magnet with which it is associated, means whereby said armatures are operatively connected with each other, said armatures being movable in unison and also relatively with respect to each other, the first part of the movement upon the energizing of the said electro-magnets causing movement of the second named armature from neutral into non-neutral position, whereby further movement thereof is effected by the action thereon of the magnet with which it is associated, and the said

6
arm having connection with the last mentioned armature and being movable therewith.

7. In a railway signaling device, the combination of a plurality of electro-magnets, rotatable armatures for said magnets, means for causing the said armatures to rotate together, the said means permitting relative rotation of said armatures, and a signal member secured to one of said armatures and rotating therewith.

8. In a signaling device, the combination of a plurality of electro-magnets, rotatable armatures therefor, means for operatively connecting the said armatures, the said means being adapted to cause the said armatures to rotate simultaneously and to permit relative rotation thereof, a signal arm secured to one of said armatures, the latter being adapted to be driven by the other when the magnet of said other is energized to cause movement of said arm part way through its path, further movement of said arm being effected by independent rotation 25 of the armature to which said arm is secured.

9. In a light signaling device, the combination of an electro-magnet, and a rotatable armature therefor, a second electro-magnet and a rotatable armature therefor, the first named armature normally being in active position and the second named in inactive or neutral position, means for limiting the

extent of rotation of the first named armature, a connection between the said armatures whereby rotation of the first named armature causes corresponding rotation of the second armature to carry it into active position with respect to its magnet after which it may continue to rotate independently of the first named magnet, and a signal arm connected to said second named armature.

10. In a light signaling device, the combination of an electro-magnet, and a rotatable armature therefor, a second electro-magnet and a rotatable armature therefor, the first named armature normally being in active position and the second named in inactive or neutral position, means for limiting the extent of rotation of the first named armature, a connection between the said armatures whereby rotation of the first named armature causes corresponding rotation of the second armature to carry it into active position with respect to its magnet after which it may continue to rotate independently of the first named magnet, and a signal arm connected to said second named armature and a light associated with said arm.

In testimony that I claim the foregoing as my invention, I have hereunto set my hand this 13th day of February, A. D. 1918.

ELOF H. MEDÉN.
